PAUL B. T. BERNER, OF BROOKLYN, NEW YORK.

DESIGN FOR A PHONOGRAPH-HORN.

No. 38,275.

Specification for Design.

Patented Oct. 9, 1906.

Application filed May 24, 1906. Serial No. 318,594. Term of patent 14 years.

To all whom it may concern:

Be it known that I, PAUL B. T. BERNER, a citizen of the United States, residing at Brooklyn, in the county of Kings and State of New York, have invented a new, original, and ornamental Design for a Phonograph-Horn, of which the following is a specification.

This invention relates to a new, original, and ornamental design for a phonograph-horn, as illustrated in the accompanying drawing, forming part thereof.

The figure is a perspective view of a phonograph-horn, showing my new design.

The horn as seen presents the appearance of a parabolic outline.

I claim—

The ornamental design for a phonograph-horn, as shown.

PAUL B. T. BERNER.
